(57) **CLAIM**

The ornamental design for a trigger guard for a firearm having a magazine well attachment, as shown and described.

DESCRIPTION

This application is related to U.S. application Ser. No. 29/507, 033 filed Oct. 23, 2014 titled Magazine Well Attachment for a Firearm. The disclosure of that application is incorporated herein in their entirety by reference.

FIG. 1 is a top, left side, perspective view of a trigger guard for a firearm having a magazine well attachment, the magazine well attachment being shown in broken lines.

FIG. 2 is a right side elevation thereof, with a portion of the receiver of the firearm and the magazine well attachment shown in broken lines;

FIG. 3 is left side elevation thereof, with the magazine well attachment shown in broken lines;

FIG. 4 is a bottom view thereof, with the magazine well attachment shown in broken lines;

FIG. 5 is a top view thereof, with the magazine well attachment shown in broken lines;

FIG. 6 is a front end view thereof, with the magazine well attachment shown in broken lines; and,

FIG. 7 is a back end view thereof, with the magazine well attachment shown in broken lines.

The magazine well attachment in FIGS. 1-7 shown in broken lines forms no part of the claimed design.
